JOSEPH C. FIELD, OF ORANGE, NEW JERSEY, AND FERDINAND ZOGBAUM, OF NEW YORK, N. Y., ASSIGNEES TO WESTERN ELECTRIC COMPANY, INCORPORATED, OF NEW YORK, N. Y., A CORPORATION OF NEW YORK.

CONTROL AND INDICATING SYSTEM FOR ELECTRIC RAILWAYS.

Application filed September 28, 1923. Serial No. 665,307.

This invention relates to control and indicating systems for electric railways, on which an application in part was filed in France on October 11, 1922, application No. 5 164,798.

It is an object of the invention to provide a new and improved system for controlling the application of feeder current to a sectionalized electric railway and for indicating at a central control station the condition of the controlling mechanisms.

The invention provides a system for sectionalized railways in which the third rail of each section is energized through a plurality of circuit breakers disposed at intervals along the track. Means is provided whereby the operator at the control station may open or close any circuit breaker within the section under his supervision and at 10 once receive an answer-back signal to indicate that the operation has been completed. Means is also provided whereby the passage of an overload current through any circuit breaker will cause that breaker to be 15 opened and will also automatically cause the other breakers feeding that particular section to be opened.

As an additional feature, the invention provides a plurality of emergency switches 20 located at intervals along the track whereby the power may be cut off from any track section in case of wrecks or other emergencies. A special signal is provided at the control station to notify the attendant when the circuit breakers are opened due to the 25 operation of one of the emergency switches.

Other features and advantages of the invention will be apparent from a consideration of the following description and the 30 accompanying drawings which when joined together with Fig. 1 placed vertically at the left and Fig. 2 horizontally at the right illustrate diagrammatically one embodiment of the invention.

45 Referring to the drawing, for the sake of clearness only one section of a double track sectionalized railway is shown. This section comprises two contact conductors 5 and 6, such as third rails, trolley wires, or the like 50 serving east and west-bound traffic, respectively, and a common main or feeder circuit 7 which is energized by a source of current 8. The current from the feeder 7 is supplied

to the rails 5 and 6 through a plurality of circuit breakers, the breakers 9, 11 and 55 13 feeding the rail 6, and the breakers 10, 12 and 14 feeding the rail 5. The breakers 9 and 10 are located at the control station shown in Fig. 1 which is preferably at one end of the track section. The breakers 11 60 and 12 are preferably grouped near the center of the section, while the breakers 13 and 14 are located near the other end of the track section. Other track sections identical to that shown in the drawings may also be 65 fed from the common feeder circuit 7.

The energizing current for the third rail 6 may be traced from the source of current 8, through feeder 7, conductor 15, contact arm 16 of solenoid 17, resistance 18 in shunt of 70 overload relay 19, part of the current passing through relay 19, conductor 20 to rail 6. Similarly, the current through the circuit breaker 11 may be traced from the source of current 8, through feeder 7, conductor 21, 75 contact arm 22 of solenoid 23, resistance 24 in shunt of overload relay 25, part of the current passing through relay 25, conductor 26 to rail 6. In the same manner, current is 80 also fed to the rail 6 through the breaker 13 and is fed to the rail 5 through breakers 10, 12 and 14. The circuit breaker 9 is normally maintained in the closed position shown in the drawing by means of a latch 27, controlled by a tripping magnet 28, which latch 85 engages a corresponding catch on the core of solenoid 17. The tripping magnet 28 is controlled by a three-position polarized relay 29 and is operable over a circuit extending from one side of battery 30, through conductor 31, tripping magnet 28, conductor 32, contact arm 33 of solenoid 17, conductor 34, contact 35 and armature of relay 29 to the other side of battery 30. The solenoid 17 is controlled by a relay 36 which in turn is 90 controlled by the polarized relay 29. The energizing circuit of the relay 36 extends from one side of battery 30, through the winding of relay 36, conductor 37, contact arm 38 of solenoid 17, conductor 39, contact 39 and armature of relay 29 to the other side of battery 30. Upon the operation of the relay 36 an energizing circuit is established for the solenoid 17 which extends from one 95 side of battery 30 through the armature and contact 40 of relay 36, conductor 41, wind-

ing of solenoid 17, conductor 42, to the other side of battery 30. The circuit breaker 11 is provided with a tripping magnet 44 corresponding to the magnet 28 of the circuit breaker 9. This tripping magnet is controlled by a three-position polarized control relay 45, the energizing circuit of the tripping magnet including a local battery 46 in a manner similar to that described above. 10 The solenoid 23 is controlled by a relay 47 which is also controlled by the polarized relay 45. All the other circuit breakers 10, 12, 13 and 14 are equipped with apparatus identical to that described in connection with the circuit breakers 9 and 11. For 15 the sake of clearness, the following description of the operation of the system has been grouped under three separate headings which treat, respectively, with the control and indication, the automatic control and indication, and the emergency control and indication.

Control and indication.

25 A plurality of red and green signal lamps are provided at the control station to indicate to the attendant the condition of the various circuit breakers. The lamps 50 and 51 are allotted to the circuit breaker 9 and 30 the lamps 52 and 53 to the circuit breaker 10. Similarly, the lamps 54 and 55 are allotted to the circuit breaker 11 and lamps 56 and 57 to circuit breaker 12, while lamps 58, 35 59 and 60, 61 indicate the position of breakers 13 and 14, respectively. One or the other of each of these pairs of lamps is normally lighted, the lighting of a red lamp indicating that a particular circuit breaker is closed, and the lighting of a green lamp indicating that its associated breaker is open. 40 In condition of the circuit shown in the drawing, it is assumed that all of the circuit breakers are closed and, accordingly, that all of the red lamps are lighted. The 45 lamps 50, 51, 52 and 53, because of their proximity to the circuit breakers 9 and 10, are controlled directly from auxiliary contacts on these breakers. Thus, when the circuit breaker 9 is closed, the red lamp 50 is 50 energized over a circuit extending from one side of local battery 62, through conductor 63, lamp 50, conductor 64, contact arm 65 of solenoid 17, conductors 66 and 67 to the other side of battery 62. If now the circuit breaker 9 is opened, the red lamp 50 will be 55 extinguished and the green lamp 51 will be energized over a circuit extending from one side of battery 62, through conductor 68, lamp 51, conductor 64, contact arm 65 of solenoid 17 which is now in its downward position, conductors 69 and 70 to the other side of battery 62. The circuits of the lamps 52 and 53, which indicate the position of the 60 circuit breaker 10, are similar to the circuits of the lamps 50 and 51, respectively.

Since the circuit breakers 11, 12, 13 and 14 are located at a distance from the control station, the indicating lamps allotted to these breakers are controlled through suitable polarized relays. Polarized relay 71 70 controls the lamps 54 and 55 and polarized relay 72 controls lamps 56 and 57. Similarly, relay 73 controls lamps 58 and 59, and relay 74 controls lamps 60 and 61. Since the circuit breaker 11 is closed, the polarized 75 relay 71 is energized over a circuit extending from the positive side of control battery 75, through conductors 76 and 77, contact arm 78 of solenoid 23, conductors 79 and 80, windings of polarized relay 71, conductors 81 and 82 to the negative side of battery 75. Since the current operating the polarized relay 71 is of positive polarity, the armature of this relay is attracted to its lower winding, lighting the lamp 54 over a circuit extending from one side of battery 62, through conductor 68, armature of relay 71, lamp 54, conductor 63 to the other side of battery 62. If now the circuit breaker 11 is opened, the polarized relay 71 will be energized over a 90 circuit extending from the negative side of battery 83, through conductors 84 and 85, contact arm 78 of solenoid 23 which is now in its lower position, conductors 79 and 80, windings of polarized relay 71, conductors 95 81 and 82 to the positive side of battery 83. Since the current operating the polarized relay 71 is of negative polarity, the armature of this relay is attracted to its upper winding, extinguishing the lamp 54 and lighting 100 the lamp 55 over a circuit extending from one side of battery 62, through conductor 68, lamp 55, armature of relay 71 conductor 63, to the other side of battery 62. The lighting of the green lamp 55 at once indicates to the attendant at the control station that the circuit breaker 11 has been moved to the open position. The operation of the polarized relays 72, 73 and 74 associated, respectively, with the circuit breakers 12, 13 110 and 14 is similar to that described above in connection with relay 71.

In accordance with a feature of the invention, the attendant at the control station may open or close any circuit breaker within in the track section under his supervision. This feature is provided in order to allow the attendant at the control station to open a circuit breaker which may be under repair at that point. Since the breakers 9 and 10 are located at the control station, it is assumed that these breakers may be operated manually by means of the usual handles provided on the cores of the trip magnets. The outlying circuit breakers, however, are controlled electrically by means of control keys located at the control station, and it is to be understood that the circuit breakers 9 and 10 may also be controlled in this manner if desired. Circuit breaker 11 may be 120

opened or closed by means of the control key 87 and circuit breaker 12 by the control key 88, while circuit breakers 13 and 14 are controlled by keys 89 and 90, respectively. If, for example, the attendant at the control station wishes to open the circuit breaker 11, he will simply throw key 87 to the right, thus operating control relay 45 of circuit breaker 11 over a circuit extending from the positive side of battery 75, through conductors 76 and 91, key 87, contact 92 of control relay 93, conductor 94, windings of polarized control relay 45, conductor 82 to the negative side of battery 75. The operation of relay 45 by current of positive polarity operates the tripping magnet 44 over a circuit extending from one side of battery 46, through conductor 104, magnet 44, conductor 105, contact arm 106 of solenoid 23, conductor 107, contact 108 and armature of relay 45 to the other side of battery 46, thus opening the circuit breaker 11. The key 87 is held in its operated position long enough to permit these circuit connections to be completed and is then released and allowed to return to the neutral position shown in the drawing. If it is now desired to close the circuit breaker 11, the control key 87 is thrown to the left, thus operating the polarized control relay 45 with current of negative polarity, over a circuit extending from the negative side of battery 83, through conductors 84 and 95, control key 87, contact 92 of polarized relay 93, conductor 94, windings of polarized relay 45, conductor 82 to the positive side of battery 83. In the same manner the circuit breakers 12, 13 and 14 may be opened or closed by the control keys 89, 88 and 90, respectively, and upon such operation of any circuit breaker an answer-back signal will be given by the colored lamps at the control station, as described above.

Automatic control and indication.

The automatic control and indication circuit is arranged so that if any individual circuit breaker opens on ground or overload, all the other circuit breakers feeding that particular section will be opened at the same instant, thereby cutting the power entirely off one complete track section. If an excess current passes through the relay 19 of circuit breaker 9 due to a ground or overload, this relay is operated and its contacts 97 and 98 are closed. The tripping magnet 28 of circuit breaker 9 is thereupon operated over a circuit extending from one side of battery 30, through conductor 42, contact 98, contact arm 33 of solenoid 17, conductor 32, trip magnet 28, conductor 31 to the other side of battery 30. The operation of the trip magnet 28 opens the circuit breaker. At the same time, the polarized control relay 93 at the control station is operated over a circuit extending from the positive side of battery 75, through conductors 76 and 99, contact 97 of overload relay 19, conductors 100 and 200, relay 130, conductors 102 and 82 to the negative side of battery 75. Relay 130 attracts its armature closing the following circuit to operate polarized relay 93, positive side of battery 75, conductors 76, 201, contact 132 of key 128, conductor 137, armature and front contact of relay 130, conductors 75 202, 101, relay 93, conductors 102, 82 to negative side of battery 75. Since the current operating the polarized relay 93 is of positive polarity, the armature of this relay will be attracted to its lower winding, thus opening contact 92 and closing contact 103. The closing of contact 103 completes an operating circuit for the polarized control relay 45 of the circuit breaker 11 which extends from the positive side of battery 75, through conductors 76 and 91, contact 103 of polarized relay 93, conductor 94, windings of polarized relay 45, conductor 82 to the negative side of battery 75. Since the current operating the polarized control relay 45 is of positive polarity the armature of this relay will be attracted to its lower winding, thus operating the tripping magnet 44 over a circuit extending from one side of battery 46, through conductor 104, tripping magnet 44, conductor 105, contact arm 106 of solenoid 23, conductor 107, contact 108 of relay 45 to the other side of battery 46, thus opening the circuit breaker 11. At the same time, the operation of relay 93 also closes contact 110 which causes the opening of the circuit breaker 13 over the conductor 111. If an excess current passes through relay 25 of circuit breaker 11, this relay is operated and its contacts 97', 98' are closed. The trip magnet 44 of circuit breaker 11 is thereupon operated over a circuit extending from one side of battery 46, through conductor 104, magnet 44, conductor 105, contact arm 106 of solenoid 23, conductor 107, contact 98' of relay 25 to the other side of battery 46. The operation of the trip magnet 44 opens the circuit breaker. At the same time the relay 130 at the control station is operated over a circuit extending from the negative side of battery 83, conductors 84, 203, contact 97' of relay 24, conductors 204, 119, 200, relay 130, conductor 102 to the positive side of battery 83. Relay 130 operates, operating relay 93 as previously described, and also closes the circuit of polarized relay 29 in parallel with relay 93. Relay 29 operates the trip magnet of circuit breaker 9, and relay 93 operates the trip magnet of breaker 13. Similarly, the operation of any one of the circuit breakers 10, 12 or 14, due to ground or overload, will operate the polarized control relay 112 at the control station which will complete circuits for operating the control relays of the other circuit break-

ers associated with the track section 5, opening these breakers in the manner described above.

5 *Emergency control and indication.*

The emergency control and indication circuit is for the purpose of cutting out individual track sections in case of wrecks and other emergencies, and is accomplished by 10 the manual operation of emergency push button switches which may be located any desired distance apart along the railroad track. Two such switches are preferably grouped together, such as switches 113, 114 15 and 115, 116. The switches 113 and 115 serve to open the circuit breakers 9, 11 and 13 while the switches 114 and 116 control the circuit breakers 10, 12 and 14. Thus 20 the power may be cut off entirely from, say the east-bound track, while west-bound traffic may proceed in the usual manner.

The operation of the emergency system at the control station is much the same as the automatic operation described above, with 25 the addition of an indicating relay for each of the track sections 5 and 6. If, in the event of a wreck on the line, it is desired to cut off the current to the track section 6, this may be accomplished by closing either 30 of the push button switches 113 or 115. If the switch 113 happens to be nearest to the scene of the disaster, the closing of this switch will complete a circuit for the operation of relay 130 at the control station, this 35 circuit extending from the positive side of battery 75 through conductors 76 and 117, switch 113, conductors 118, 119 and 200, relay 130, conductors 102 and 82 to the negative side of battery 75. The operation of 40 relay 130 operates the relays 29 and 93 as described which in turn operate their trip magnets 28 to 44 respectively. At the same time the control relay of the circuit breaker 13 is also operated as described. An indicating 45 relay is provided at the control station for each of the track sections 5 and 6. The indicating relay 122 is associated with the track section 6 and the relay 123 with the track section 5. The operation of the relays 50 122 and 123 will light indicating lamps 124 and 125, respectively, which are separate from the indicating lamps described above. These indicating lamps are for the purpose of showing the operator at the control station 55 that the circuit breakers feeding a certain track section have been opened by the operation of an emergency push button switch and not by the operation of the automatic overload circuit. When the push button 60 switch 113 is operated as described above, a circuit is completed for operating the indicating relay 122 over a circuit extending from the positive side of battery 75, through conductors 76 and 117, switch 113, 65 conductors 118, 119 and 200, 205 and 206,

windings of polarized relay 122, conductors 102 and 82 to the negative side of battery 75. The operation of the polarized relay 122 by current of positive polarity closes its contact 127, thus lighting the emergency 70 lamp 124 over a circuit extending from one side of battery 62, through conductor 63, contact 127 of relay 122, lamp 124, conductor 68 to the other side of battery 62. Relay 122 may also be operated in the same manner by the closure of the emergency switch 115. Both the polarized relay 93 and the polarized relay 122 will remain in the position last operated until restored to their 75 normal positions by the operation of a restoring key 128. Similarly, the polarized relays 112 and 123 will remain in their operated positions until restored by the operation of a restoring key 129. Relay 130 also acts to restore polarized relays 93 and 122 80 and relay 131 also acts to restore relays 112 and 123. Assuming that the relays 93 and 112 are in their operated positions with their armatures attracted to their lower windings, respectively, the operation of key 128 opens contact 132 and closes contacts 133 and 134. The closure of contact 133 operates the relay 130 over a circuit extending from the negative side of battery 83 through conductors 84 and 135, contact 133 85 of key 128, winding of relay 130, conductors 102 and 82 to the positive side of battery 83. The operation of relay 130 closes its contact 136, thus operating relay 93 over a circuit extending from the negative side 90 of battery 83 through conductors 84 and 135, contact 134 of key 128, conductor 137, armature and contact 136 of relay 130, conductors 202, 101, windings of relay 122, conductor 102, conductor 82 to the positive side 95 of battery 83. Contact 133 of key 128 closes a circuit to restore relay 122. The operation of the polarized relays 93 and 122 by current of negative polarity causes the 100 armatures of these relays to be attracted to their upper windings and to return them to the normal position shown in the drawing. With the return of relay 122 to the normal position shown in the drawing the emergency lamp 124 is extinguished. In a like 105 manner, the operation of restoring key 129 operates the restoring relay 131 and serves to return the polarized relays 112 and 123 to normal, in which condition it will again be ready to respond to the operation of the 110 emergency push buttons 114 and 116. Since it is obvious that many changes may be made in this system without departing from the scope and spirit of the invention, it is not intended to limit the invention to the 115 specific construction herein shown and described except as defined by the appended claims.

What is claimed is:

1. A control and indicating system com- 120

- prising a central station and a plurality of circuit breakers remote therefrom, an electric conductor supplied with current through said circuit breakers, means at said central station for selectively operating said circuit breakers, means including a relay at said central station for controlling the operation of said circuit breakers, means controlled by the passage of a predetermined amount of current through any of said circuit breakers for operating said relay, means at said central station for giving a distinctive signal upon the operation of any circuit breaker, means including a switch remote from said central station for controlling the operation of said relay, and means at said central station controlled by the operation of said switch for giving an additional indication thereof.
2. A control and indicating system comprising a central station and a plurality of circuit breakers remote therefrom, an electric conductor supplied with current through said circuit breakers, means at said central station for selectively operating said circuit breakers, means at said central station for giving a distinctive indication of such operation, an overload relay associated with each of said circuit breakers and adapted to be operated by the passage of a predetermined current through the conductor, a polarized relay at said central station, means controlled by the operation of any of said overload relays to energize the polarized relay with one polarity, means controlled by said polarized relay for operating said circuit breakers, means including an electric switch remote from said central station to energize with the same polarity said polarized relay, a second polarized relay at said central station energized with one polarity by the operation of said switch, a distinctive signal controlled by said second polarized relay, a restoring key at said central station, and means controlled by the operation of said key for energizing the polarized relays with opposite polarity and thereby returning said polarized relays to their normal positions.

In witness whereof, we hereunto subscribe our names this 25th day of September, A. D. 1923.

JOSEPH C. FIELD.
FERDINAND ZOGBAUM.
